PORTABLE SODA FOUNTAIN

Frank A. Turiace, Jr., 2820 N. Main St.,
Los Angeles, Calif.

Filed Feb. 7, 1966, Ser. No. 947

Term of patent 14 years

(Cl. D2—3)

FIG. 1 is a perspective view as seen from the top, of a portable soda fountain, showing my new design.

FIG. 2 is a perspective front view thereof, to a reduced scale.

FIG. 3 is a perspective rear view, to the scale of FIG. 2. The dominant features of the design are shown in the drawing in full lines.

I claim:

The ornamental design for a portable soda fountain, substantially as shown and described.
